UNITED STATES PATENT OFFICE.

LEONARD J. HAAS, OF NEW YORK, N. Y.

DESIGN FOR A LADY'S VEST.

SPECIFICATION forming part of Design No. 19,687, dated March 4, 1890.

Application filed January 22, 1890. Serial No. 337,739. Term of patent 3½ years.

To all whom it may concern:

Be it known that I, LEONARD J. HAAS, a citizen of the United States, residing at New York city, in the county and State of New York, have invented and produced a new and original Design for Ladies' Vests, of which the following is a specification, reference being had to the accompanying drawing, forming a part thereof.

10 The drawing illustrates a plan view of the completed design.

The side outlines a of the vest are shaped to a compound curve, the bottom edge a' being given an angular or pointed appearance, 15 and in the center of the upper portion of the top two concentric circular lines a^2 are drawn, whereby a collar-like figure A is formed. The upper outlines a^3 at each side of the center

are drawn angular or pointed. A center line b extends from top to bottom, and button-like figures b' appear at intervals upon said line, and at each side of the center line a shorter line b^2 is drawn, presenting the appearance of a gore. Band-like figures d are drawn upon the face of the vest at the bottom, and other band-like figures d' are formed at the top. Tape-like figures D are represented as intersecting the opposed side marginal edges near the bottom.

I claim—

A design for ladies' vests, substantially as herein shown and described.

LEONARD J. HAAS.
